(57) **CLAIM**

The ornamental design for an automatic injection device, as shown and described.

DESCRIPTION

FIG. 1 is a side view of an automatic injection device showing our new design;

FIG. 2 is a front view thereof;

FIG. 3 is an opposite side view thereof;

FIG. 4 is rear view thereof;

FIG. 5 is a top view thereof; and,

FIG. 6 is a bottom view thereof.

The broken lines in the Figures showing internal portions and external pocket portions of the automatic injection device form no part of the claimed design.
